US00D928949S

(12) **United States Design Patent** (10) Patent No.: **US D928,949 S**
(45) Date of Patent: **** Aug. 24, 2021**

(54) **CONNECTOR**

(71) Applicant: **Fisher & Paykel Healthcare Limited**,
Auckland (NZ)

(72) Inventors: **Laurence Gulliver**, Auckland (NZ);
Michael Paul Ronayne, Auckland (NZ); **Charles William Douglas**
Irving, Auckland (NZ); **Mark Thomas O'Connor**, Auckland (NZ)

(73) Assignee: **FISHER & PAYKEL HEALTHCARE LIMITED**, Auckland (NZ)

(**) Term: **15 Years**

(21) Appl. No.: **29/751,544**

(22) Filed: **Sep. 22, 2020**

Related U.S. Application Data

CLAIM

The ornamental design for a connector, as shown and described.

DESCRIPTION

FIG. 1 is a front, top, and side perspective view of a connector.

FIG. 2 is a back, top, and side perspective view thereof.

FIG. 3 is a top view thereof, the bottom being a mirror image.

FIG. 4 is a side view thereof, the opposite side being a mirror image.

FIG. 5 is a front view thereof; and,

FIG. 6 is a back view thereof.

The broken lines in the drawings illustrate portions of the connector and form no part of the claimed design.

1 Claim, 3 Drawing Sheets
